UNITED STATES PATENT OFFICE.

SAMUEL LIPSIUS, OF NEW YORK, N. Y.

RAISED-PRINTING APPARATUS.

1,194,647.

Specification of Letters Patent. Patented Aug. 15, 1916.

Application filed September 25, 1915. Serial No. 52,582.

To all whom it may concern:

Be it known that I, SAMUEL LIPSIUS, a citizen of the United States of America, residing at New York city, New York, have 5 invented a new and useful Raised-Printing Apparatus, of which the following is a specification.

This invention has reference to that branch of the printing art known as raised 10 printing, wherein an effect similar to embossing is produced by the amalgamation of a fusible powder with the freshly printed surface.

The general objects of the invention are 15 to provide simplified and improved means for effecting the amalgamation of the fusible powder with the printed surface.

According to my invention the amalgamation is effected in an oven through which the 20 printed and powdered sheets are carried by a conveyer, and a special feature of this oven is that a uniform treatment of the sheets is obtained without scorching or under-heating the sheets by the interposition 25 of a body of heat retaining material between the sheet conveyer and the source from which it receives its heat. For the heat retaining body I preferably employ a sand-like material supported by a pan directly 30 beneath the sheet conveyer, and between said conveyer and the heater.

A gradually increasing and then decreasing heating effect is obtained by sloping the oven up from both ends toward the center 35 and by causing the conveyer to travel first upwardly toward the center and then downward to the far end of the oven, and to make this heating effect more uniform and regular, the heat retaining body beneath the conveyer is inclined upwardly and then downwardly in substantial conformity with the travel of the conveyer. Preferably, also the heater, which may conveniently be in the form of a gas burner, and which is located 40 beneath the heat retaining body, is inclined upwardly and then downwardly in substantial conformity to the outline of the heat retaining body.

The sand pan is, in a preferred embodiment 45 of my invention, of special construction embodying a strip of sheet metal made with upturned edges and transversely extending reinforcing ribs.

Another feature of my invention is the

provision of a device for cooling and thoroughly drying the treated sheets before allowing said sheets to come into contact with each other. This cooling device, as I have termed it, consists in the present disclosure of a conveyer located beneath the oven, and having its receiving end arranged to receive the heated sheet from the discharge end of the heating conveyer.

Other features and details of structure will appear as the specification proceeds. 65

In the drawings accompanying this specification I have illustrated my invention as embodied in a practical and commercial form, but it will be understood that changes and modifications may be made without departing from the true spirit and the scope 70 of the invention.

In the drawings: Figure 1 is a side elevation of apparatus embodying the invention, the entrance end of the oven being broken away and shown in section. Fig. 2 is a plan view of the same, with parts broken away. Fig. 3 is a cross sectional view of the apparatus taken substantially on the plane of the line 3-3 of Fig. 1. Fig. 4 is another cross sectional view taken substantially on the plane of the line 4-4 of Fig. 1. Fig. 5 is a partial longitudinal sectional view of the apparatus. Fig. 6 is a more or less diagrammatic view illustrating the preferred manner of making up the walls which form the sand pan and the bottom to the oven. 85

In the embodiment illustrated in the present disclosure, the oven is of substantially 90 triangular formation, and consists of a bottom 10, side walls 11 and a top 12, the side walls and top sloping from the ends of the furnace upwardly to a high point substantially mid-length of the furnace. 95

In carrying out the process of the invention, the sheets are first printed with a slow drying ink, then dusted with a powder which adheres to the inked portions and which will fuse into the ink under the action of heat, 100 and the freshly inked sheets with the fusible powder adhering to the printed portions thereof are then subjected to a heat within the oven which will fuse the powder and bring about an amalgamation thereof with 105 the printing ink. To bring about a gradual fusion of the powder with the ink without injuring the sheets by scorching or over-

heating them to such an extent as to take away their flexibility or strength, the sheets are heated gradually and it is preferable also to decrease the applied heat gradually.

- 5 After this heat treatment the sheets are preferably cooled to dry and set the amalgamated powder and ink.

The gradual heating of the sheets is accomplished in the present form of the invention, by reason of the triangular construction of the oven, and by the employment of a conveyer which extends on an incline up to the highest portion of the oven, and so, carries the sheet gradually up into the zone of greatest heat. This conveyer is designated 15 and is shown in the form of an endless belt supported at the ends on rollers 16 and 17, and at the center by a roller 18, this center roller being supported well up in the 20 apex of the oven, so as to cause the conveyer to traverse first an upward incline, and then a downward incline. The lower run of the conveyer may be supported on suitable idlers 19. This conveyer is of special construction, 25 it being made of relatively closely woven wire mesh work, which permits free access of the heat to the sheet on the conveyer, and at the same time prevents the sheet slipping through the interstices in the conveyer, and 30 which if not so provided against would be likely to occur on account of the inclination of the conveyer. Heat may be supplied from any suitable source and the same is provided in the present disclosure by a gas burner 20 located in the oven beneath the conveyer and supplied with fuel through a suitably regulated supply pipe 21. A special feature of this burner or heater, is that it is inclined in substantial conformity to the path of movement of the conveyer, so as to apply the heat more uniformly to said conveyer.

A relatively quick fusion of the powder is obtained and without the danger of scorching or injuring the sheets by interposing a heat retaining medium or body between the heater and the conveyer. This medium is provided in the present instance by a body of sand 25 supported in a pan 26, and a special feature of this pan is that it, like the 45 burner, substantially follows the inclination of the conveyer. In the preferred construction this sand pan is supported between the side walls of the oven, but a space 27 is left between the side walls and the edges of the 50 pan to allow circulation of the heated air from the heater around the edges of the pan and into contact with the sheets on the conveyer. This sand pan is of novel construction, it being for one thing provided with 55 transversely extending ribs 28 dividing it into a series of sand trays. This construction prevents the shifting of the sand which would otherwise occur due to the inclination of the pan. Preferably the sand pan is made 60 of sheet metal and the separating ribs or

ridges are provided by striking up the metal of the sheet metal strip from which the pan is made on transverse lines.

In Fig. 6 I have illustrated a practical and preferred method of constructing the 70 sand pan. In this view, the blank strip 30 of sheet metal is first formed with oppositely disposed notches 31 in the edges thereof, then the metal between opposite notches is bent up on the lines 28' to form 75 the upstanding ribs 28, and finally the edge portions 32 of the strip between adjacent ribs are turned up to form retaining walls 33 at the edges of the pan. The ribs are of less width than the notches, as indicated by 80 the dotted lines 28', leaving portions 34 at each side of the top of the rib, which constitute when the ribs are bent up into shape, the sides of the ribs. When the edge portions 32 are bent up into place, their end 85 faces 35 engage the side walls 34 of the rib as indicated, thereby forming shallow trays between the ribs. This construction provides a very rigid and comparatively inexpensive form of pan for containing the sand. 90 I prefer to utilize this form of construction also for the bottom of the oven and have, therefore, illustrated the bottom wall as being constructed in the manner just described and similar to the wall which forms the pan. 95

The sand pan is supported by the side walls but spaced away therefrom by providing inwardly projecting supporting lugs 35 on the sides on which the pan rests, these lugs being of a size to enter in under the 100 upstanding ridges substantially as indicated in Figs. 1 and 4.

The oven structure is preferably supported on angle bars or sills 37 extending the full length of the oven and mounted on 105 suitable posts 38. A convenient and very practical manner of securing the walls of the oven together is by means of the through bolts indicated at 39, which pass through the side walls and serve to clamp the bottom wall and the sand pan between said sides.

A sight opening 40 may be provided in the top, preferably at the highest point therein, and another sight opening may be 115 provided in the side wall, as indicated at 41, these two openings being normally closed by the transparent closures 42 and 43 so that the heating effect may be observed without interrupting the operation of the 120 apparatus.

In using the apparatus thus far described, the sheets, after being printed and powdered with the fusible powder, are placed upon the heating conveyer at the right hand 125 end of the oven in Fig. 1, and are carried by said conveyer into the oven and upward gradually into the zone of greatest heat at the top of the oven. From this zone of greatest heat the sheets are carried down-

ward and out at the left hand end of the oven. During this passage, the powder is gradually fused and becomes amalgamated with the printing ink and except for the fact that the amalgam may be somewhat soft when the sheets are discharged from the oven, they are complete and ready for use.

To harden the amalgam and render the treated sheets ready for use at once, I have

10 provided a cooling device in the form of a conveyer 45 traveling beneath the oven and having its receiving end located beneath the discharge end of the heating conveyer so as to receive the heated sheets therefrom. This 15 cooling conveyer is shown as an endless belt supported on rollers 46 and 47, and an inclined guide or chute 48 is shown provided for directing the sheets from the heating conveyer down on to the cooling conveyer, 20 a box 49 at the receiving end of the cooling conveyer serving further to guide the sheets. The supporting surface of the cooling conveyer is disposed beneath and separated from the oven by an air space, so that 25 the sheets will not be materially affected by the heat of the oven. In the passage of the sheets upon the cooling conveyer, the amalgam cools and hardens, and at the end of their travel on this conveyer, the sheets 30 may be discharged into any convenient form of receptacle or receiver 50.

The conveyers may be driven by any suitable gearing, and the same consists in the present instance of a drive shaft 52 provided 35 with a pulley 53 belted to an electric motor and carrying a worm 54 engaging a worm wheel 55 on the shaft 56 which carries the conveyer supporting roller 17, motion being transmitted from a pulley 57 on this shaft 40 through a belt 58 to another pulley 59 on the shaft 60 of the cooling conveyer roller 46.

It will be noted that the idler rollers 19, which are located at the ends of the oven substantially close the ends so as to prevent 45 loss of heat. Preferably also the top is brought down relatively close to the conveyer, leaving only space sufficient for the feeding in and discharge of the sheets. By reason of these facts, and the peaked construction of the oven, the heat is so confined and controlled that there is practically no waste. At the start, enough heat is supplied to thoroughly heat the heat retaining body, and when this point is reached the heat can 50 be cut down to a condition where the desired heat will be maintained. The use of this heat retaining body in connection with the other features described, therefore, serves to conserve the heat and secure efficient operation with a relatively small fuel 55 consumption.

In cooling the sheets by means of the cooling conveyer, one man, in the case of manual feeding, is enabled to attend to the entire 60 machine, since the finished sheets are re-

turned back to a point closely adjacent the feeding-in station, and within convenient reach of the operator. The use of this cooling conveyer furthermore increases the capacity of the machine, since the machine can 70 be worked at a higher rate of speed as there is no delay in waiting for the treated sheets to cool and dry.

What I claim is:

1. In apparatus for producing raised printing, an oven, a conveyer traveling through said oven, a sand pan beneath the conveyer having partitions dividing said pan into a plurality of sand trays and a heater beneath said sand pan. 75

2. In apparatus for producing raised printing, an oven, a conveyer traveling through said oven, a sand pan arranged on an upward incline beneath said conveyer and provided with upstanding partitions dividing said pan into a plurality of sand trays and a heater beneath said sand pan. 85

3. In apparatus for producing raised printing, an oven having spaced apart sides and a top, a sand pan supported between 90 said sides and having upturned edges spaced inwardly from said sides, a conveyer traveling through the oven above said sand pan, and a heater beneath said sand pan.

4. In apparatus for producing raised printing, an oven, a conveyer traveling through said oven, a sand pan in said oven having upturned edges spaced apart from the walls of the oven and partitions dividing said pan into a plurality of sand trays, 100 and a heater below said sand pan. 95

5. In apparatus for producing raised printing, an oven, a conveyer traveling through said oven and adapted to carry a freshly inked and powdered sheet in an upward and then downward direction, a heat retaining body beneath said conveyer inclined upwardly from its opposite ends into the apex of the conveyer and forming a heat pocket beneath said apex of said conveyer 110 and a source of heat beneath said heat retaining body. 105

6. In apparatus for producing raised printing, an oven, a conveyer traveling through said oven inclined upwardly from 115 a lower to a higher elevation and from the higher elevation to a lower elevation, a heat retaining body beneath the conveyer extending up into the apex of said conveyer and substantially conforming to the inclination 120 of said conveyer, and a heater beneath said heat retaining body substantially conforming to the inclination of said body. 125

7. In apparatus for producing raised printing, an oven of substantially triangular 125 shape, highest at the center and lower at the ends thereof, a conveyer traveling through said oven extending up into the apex of said oven, and extending downwardly toward each end thereof, a heat retaining body be- 130

- neath the conveyer extended up toward the apex of the oven and substantially conforming to the inclination of the conveyer, and thereby forming a heat pocket in the apex 5 of the oven beneath the conveyer, and a heater beneath said heat retaining body.
8. In apparatus for producing raised printing, an oven, a sheet conveyer in said oven arranged to discharge heated sheets at 10 one end of the oven, and a cooling conveyer beneath the oven, separated by a cooling air space from said oven and having its receiving end beneath and adjacent the discharge end of the conveyer in the oven and 15 receiving the printed sheets directly from said oven conveyer.
9. In an oven construction, a wall consisting of an initially flat strip of sheet metal having oppositely disposed notches cut 20 in the edges thereof, the metal of the sheet between opposite notches therein being bent upward transversely of the sheet into up-standing ribs and the edges of said strip between adjacent ribs being bent upward 25 substantially into engagement with the side walls of said ribs to form a tray-like structure braced by the transverse ribs.
10. In apparatus of the character set forth, a heater, and a conveyer for freshly 30 inked and powdered sheets above said conveyer arranged on an upward incline and constructed of wire mesh work to thereby provide free access of heat from the heater to the sheets on the conveyer without permitting said sheets to fall down through the 35 inclined conveyer.

11. In apparatus for producing raised printing, an oven, a conveyer traveling through said oven and adapted to carry a freshly inked and powdered sheet in an upward and then downward direction, a heat retaining body beneath said conveyer and substantially conforming in shape to the path of movement of said conveyer, a source of heat beneath said heat retaining body, 40 and a cooling conveyer beneath the oven having its receiving end disposed adjacent the discharge end of the heating conveyer to receive the heated sheets therefrom.
12. In apparatus for producing raised 45 printing, an oven, a conveyer traveling through said oven and adapted to carry a freshly inked and powdered sheet, a heat retaining body beneath said conveyer, a source of heat beneath said heat retaining 50 body, a cooling conveyer beneath the oven having its receiving end disposed beneath and adjacent the discharge end of the heating conveyer to receive the heated sheets therefrom, and an inclined chute guiding the 55 sheets from the oven conveyer onto the cooling conveyer printed side up.

13. In apparatus for producing raised printing, an oven having spaced apart sides, and a top, a conveyer traveling through said 60 oven, a heater beneath said conveyer and a sand pan interposed between said heater and the conveyer protecting articles on said conveyer from the direct effect of the heater and providing passages for the flow of heat 65 from said heater to said conveyer.

SAMUEL LIPSIUS.
